L. E. RUTLEDGE

REVERSIBLE COTTON SACK

Filed April 5, 1923

INVENTOR.

Lucy E. RUTLEDGE.
BY
J. H. Weatherford
ATTORNEY

UNITED STATES PATENT OFFICE.

LUCY E. RUTLEDGE, OF EADS, TENNESSEE, ASSIGNOR OF ONE-FOURTH TO JOHN M. BRAUN, OF MEMPHIS, TENNESSEE.

REVERSIBLE COTTON SACK.

Application filed April 5, 1923. Serial No. 630,045.

To all whom it may concern:

Be it known that I, LUCY E. RUTLEDGE, a citizen of the United States, residing at Eads, in the county of Shelby and the State of Tennessee, have invented a certain new and useful Improvement in Reversible Cotton Sacks, of which the following is a full, clear, and exact description, such as will enable anyone skilled in the art to make and use the same.

My invention relates to improvements in sacks in which cotton is placed, as it is picked from the stalk in the cotton field, and has especial reference to sacks which may be turned end for end after they have been used, whereby the length of life of the same may be prolonged.

In picking cotton by hand, it has been found most satisfactory for the person doing the picking to have a long bag hung from his shoulders, with an open mouth at the top and a closed bottom end, which bottom end drags along on the ground behind him. The cotton picked by hand is stuffed in the mouth of this sack until the same is full and it is then necessary for the cotton picker to take the sack off his shoulder and shake the cotton out into a basket or other receptacle so that he may again start filling the sack. The wear on a sack of this kind is very rapid and it quickly becomes unfit for use. In addition, the sack is often dragged through mud and in emptying it, the hands become muddy and either a considerable amount of cotton is wasted in cleaning the hands to begin again, or the first cotton picked thereafter is damaged by the dirt on the picker's hands. In an endeavor to get away from these faults, double ended or reversible sacks have been used, but these while improving the conditions, get into other troubles which are practically as bad. The fastening means in these double ended sacks are exposed, the reversible ends are exposed and after such use as is necessary, to require the sack to be turned, it is often found that the former bottom end which is designed to be turned upward, is so badly damaged it cannot be used, and the reversible feature of the sack is entirely lost. It is these features, which in my improved sack I have corrected. With these points in view, the objects of my invention, are;

First: To provide means whereby the

sack may be reversed four times, thus providing a quadruple life for the same. 55

Second: To provide means whereby the portions of the sack subject to wear are reinforced.

Third: To provide closure means by 60 which either end of the sack may be closed and used for a bottom.

Fourth: To provide means whereby the closure fastenings will be protected from wear and will also be protected against 65 mud and dirt so that they may be usable even though the sack be dragged through mud and become covered with the same.

Fifth: To provide a satisfactory mouth for that end of the sack which may be used 70 for the upper end, and

Sixth: To generally improve the construction of the sack.

I accomplish these objects, as will be more fully hereinafter set out in the drawings, 75 specifications and claims.

In the drawings:

Fig. 1, is a view of my sack supported from the shoulder of a person ready to pick cotton, the bulging of the sack indicating 80 that it is partially filled with cotton.

Fig. 2, is a sectional perspective view of an empty sack cut parallel to the length of the sack with the thickness of materials exaggerated, and 85

Fig. 3, is a similar enlarged view showing the detail of one of the fasteners.

These sacks are ordinarily made of heavy cloth, such as canvas, khaki, or similar material. 90

Referring now to the drawings, in which the various parts are indicated by the same numerals in all the views; 1, is the body or body section of the sack, which section is open at both ends, and which when filled is adapted to take a substantially cylindrical form. At both ends of this body are flaps or extension sections, 2, 3, 4 and 5 which extension sections are substantially identical each with the other, and which are 95 of even width with the body section. Each of these extension sections is provided with a plurality of fastening means 6, these preferably being heavy buttons and for each of these buttons a corresponding button hole 100 is provided. This is preferably accomplished by means of tabs 7 with button holes 8 therein into which button holes the corre-

sponding buttons 6 are adapted to fasten. Though a single strip or member provided with similarly spaced button holes may of course be used. These tabs or members are 5 securely fastened to the body section of the sack at a distance from the end of the body substantially equal to the length of the said extension sections. 9, 10, 11 and 12 are reinforcing sections, of about the same 10 width as the body of the back section approximately one-half of which in length, is ordinarily securely fastened to the body of the sack, the other one-half being in the form of loose flaps which hang free. These 15 reinforcing sections are fastened to the body of the sack along the same line that the tabs 7 are fastened and are also additionally fastened to the body of the sack between these lines, preferably by being securely sewed 20 thereto. Such means of attachment is indicated by the dotted lines 13 in Figs. 1 and 2 and the stitches 14 in Fig. 3.

The completed sack would then consist of a central body section open at both ends 25 with four extension sections extending beyond the ends thereof and four reinforcing sections attached to the body section intermediate the ends and means for detachably securing the ends of the extension sections 30 to the body section at a point where these reinforcing sections could cover them.

It will be seen that any extension section such as the section 3 may be folded back against the body section and buttoned or 35 otherwise fastened to its intermediate, or between, the ends of the body section, or one extension section such as the section 5, may be turned within the body section and the opposite section such as the section 6 may 40 be folded over the end of the sack to form a closure therefor and be fastened to the body section as shown, and any extension section such as 1 may be left extended and a strap fastened to it to form carrying means. Any 45 reinforcing section such as 9 and 10 when at the top of the sack is adapted to fold back out of the way, and any such section such as 4 and 5 when at the bottom of the sack is adapted to extend along the sack, or to extend 50 along and beyond the end of the sack to take the wear and when so doing to cover and protect the extension flap such as 6 and attaching means therefor, against dirt and wear.

55 Manifestly the extension sections may be joined along their edges and form an outer sack section enclosing the body section of the sack and thus accomplish the same purpose as the separate extension sections.

60 After a reinforcing section, such as 11 becomes worn, the extension 2, can be folded back and fastened and the extension 3 unfastened and extended to provide thus for carrying means, and the sack rotated to bring 65 the reinforcing section 12 into position to

take the wear. Likewise the extension 2 (or 6) can be turned into the body of the sack and the corresponding extension 6 (or 2) can be folded over the end of the body section to close that end of the sack, and the section 4 then unfastened and either it or the section 5 be used as an extension section. It will thus be seen that I secure four sections adapted in turn to take the wear incident to use and yet protect the extension sections for 70 their proper purpose. Should it be desired to carry a full sack any distance the open end may be readily closed and fastened for such purpose. Should cotton be tightly packed in the closed end of the sack, this 75 may readily and easily be opened to allow cotton to be removed from that end or if desired, from both ends at the same time.

It will be realized that the various extensions should be at least as wide as the 80 body section of the sack, but this while extremely advantageous is not absolutely essential.

I prefer the button method for fastening the sack, but manifestly various other means 85 may be used, also I put the buttons on the extensions, but they may equally as well be put on the sack and the button holes or loops to receive them be put in the extensions.

Having now fully described my invention, 90 what I claim and desire to secure by Letters Patent in the United States is:—

1. In a reversible cotton sack a body section open at both ends, extension sections of 95 substantially body width extending from each end thereof and adapted to be folded back against said body section, or to be folded over the end thereof to form a closure therefor, means for detachably fastening the 100 said extension sections to said body section in either of said folded positions, reinforcing sections of substantially body width attached to said body section adjacent said fastening means and intermediate thereof, and adapted to extend outward along said 105 body section and to cover said fastening means, or to be folded back against said body section, a carrying strap and means for attaching the same to any one of said extension sections when such section is extended.

2. In a reversible cotton sack, a body section, open at both ends, extension sections of 110 substantially body width extending from each end thereof, and adapted to be folded back against said body section, or to be folded over the end thereof to form a closure therefor, buttons attached to each of said extension sections adjacent the end thereof, 115 members having corresponding button holes therein, attached to each side of said body section substantially the length of said extension section from each of the ends of said body section, reinforcing sections attached to said body sections adjacent said members 120

and intermediate the same, and adapted to extend outward along the said body section and to cover said button hole members, or to be folded back along said body section, and 5 a carrying strap adapted to be attached to the buttons on any one of said extension sections when such section is extended.

3. In a reversible cotton sack a body section open at both ends, extension sections 10 of substantially body width extending from each end thereof, and adapted to be folded back against said body section or to be folded over the end thereof to form a closure therefor, means for fastening the said 15 extension sections to said body section in either of said folded positions, reinforcing sections of substantially body width attached to said body section adjacent said fastening means and intermediate thereof 20 and adapted to extend beyond the end of said body section and to cover said fastening means, or to be folded back against said body section, a carrying strap and means for attaching the same to any one of said 25 extension sections when the same is extended.

4. In a reversible cotton sack, a body section, open at both ends, extension sections of substantially body width extending from each end thereof, and adapted to be folded 30 back against said body section, or to be folded over the end thereof to form a closure therefor, buttons attached to said extension sections adjacent the end thereof, members having corresponding button holes 35 therein, attached to each side of said body section, substantially the length of said extension section from each of the ends thereof, reinforcing sections attached to said body sections between said members and adapted 40 to extend outward along the said body section and to cover said button hole members, or to be folded back along said body section, and carrying means.

5. In a reversible cotton sack a body section open at both ends, extension sections 45 extending from each end thereof and adapted to be folded back against said body section or to be folded over the end thereof to form a closure therefor, means for fastening the said extension sections to said body section in either of said folded positions, reinforcing sections attached to said body sections between said fastening means and adapted to extend along said body sections 50 and to cover said fastening means, or to be folded back against said body section, and carrying means.

6. In a reversible cotton sack, a body section, open at both ends, extension sections

extending from each end thereof, each 60 adapted to be folded back against said body section or to be folded over the end thereof to form a closure therefor, buttons attached to said extension sections adjacent the end thereof, members having corresponding button holes therein, attached to each side of 65 said body section intermediate the ends thereof, reinforcing sections attached to said body sections between said members and adapted to extend beyond the ends of the 70 said body section and to cover said button hole members, or to be folded back along said body section, and carrying means.

7. In a reversible cotton sack a body section open at both ends, an extension section 75 of substantially body width extending from each end thereof and adapted to be folded back against said body section or to be folded over the end thereof to form a closure therefor, means for fastening the said extension section to said body section in either of said folded positions, reinforcing sections of substantially body width attached to said body section adjacent said fastening 80 means and intermediate thereof and adapted to extend along said body section and to cover said fastening means, or to be folded back against said body section, a carrying strap and means for attaching the same to either of said extension sections when the 85 same is extended.

8. In a reversible cotton sack, a body section open at both ends, extension sections of substantially body width extending from each end thereof, and adapted to be folded 90 back against said body section or to be folded over the end thereof to form a closure therefor, buttons attached to each of said extension sections adjacent the end thereof, members having corresponding button holes therein, attached to each side of 95 said body section, substantially the length of said extension section from each of the ends of said body section, reinforcing sections attached to said body sections between 100 said members, and adapted to extend beyond the ends of the said body section and to cover said button hole members, or to be folded back along said body section, and a carrying strap adapted to be attached to 105 the buttons on any one of said extension sections when such section is extended.

In testimony whereof I have hereunto set my name.
